UNITED STATES PATENT OFFICE.

JAMES H. WAGENHORST, OF AKRON, OHIO.

ARC-LAMP.

1,279,618.

Specification of Letters Patent. Patented Sept. 24, 1918.

Application filed December 24, 1912. Serial No. 738,506.

To all whom it may concern:

Be it known that I, JAMES H. WAGENHORST, a citizen of the United States, residing at Akron, in the county of Summit and State of Ohio, have invented a new and useful Improvement in Arc-Lamps, of which the following is a specification.

This invention relates generally to arc lamps, and more particularly to an arc lamp adapted for use in connection with electric blue printing machines, but it will of course be understood that the lamp as constructed and operated can be used for general lighting purposes equally as well as for electric light blue printing.

The object of my present invention is to simplify the number of parts and also their construction; to cut down the heavy starting current by the elimination of one of the coils or solenoids and replacing it with a spring mechanism which will carry approximately one-half of the load imposed by the carbon, carbon holder, dash pot and solenoid, this spring mechanism to carry its load through the clutch to assist it in holding the carbon in operative position in either direction.

With this object in view, and with certain other objects as will hereinafter appear the invention consists in the novel features of construction together with novelties of arrangement or combination all of which will be hereinafter fully described and pointed out in the claims.

In the drawings forming a part of this specification:

Figure 1 is an elevation with parts in section of an electric arc lamp constructed in accordance with my invention.

Fig. 2 is an elevation with parts in section taken from a point at right angles to the view point of Fig. 1.

Fig. 3 is a view similar to Fig. 1, but taken from the opposite side.

Fig. 4 is a sectional elevation illustrating the solenoid, dash pot and clutch.

Fig. 4^a is a detail sectional view of the dash pot.

Fig. 5 is a sectional plan view on the line 5-5 of Fig. 4.

Fig. 6 is a sectional view taken on the line 6-6 of Fig. 4.

Fig. 7 is a detail sectional view on the line 7-7 of Fig. 3.

Fig. 8 is a detail perspective view of the upper carbon holder which is adapted to work in the upper carbon guide.

Fig. 9 is a detail sectional view on the line 9-9 of Fig. 3.

Fig. 10 is a vertical sectional view of the lower carbon holder and illustrating the manner of securing the same.

Fig. 11 is a view illustrating the manner of winding the solenoid.

In the practical embodiment of my invention I employ a circular skeleton plate or frame A, to which the binding posts for the conductor wires are attached, and which also carries the lamp suspending means A'.

To the under side of this skeleton plate or frame is attached the upper end of the upper carbon guide B, this carbon guide B, being

in the form of a tube which is divided longitudinally as shown at B', the upper ends B² being spread apart as shown and secured to the under side of the top frame or plate A,

75 by the same bolts which secure the binding posts and it will also be noted that the conductor wires leading to the solenoid and lower carbon are connected to the binding posts upon the interior of the skeleton frame or plate A, as most clearly shown in Fig. 2,

80 a strip of insulation B³, being interposed between the divided ends of the upper carbon guide and the skeleton frame or plate. The lower end of the carbon guide B, is divided

85 and spread as shown at B⁴, the lower ends thereof being rigidly secured to a circular asbestos plate C, which serves the double purpose of providing points of attachment

90 for the carbon holder, dash pot and lamp brackets, and at the same time serves to

shield them from the heat generated by the lamp, and thereby prevents this heat being transmitted to the working parts of the device.

Globe carrying brackets D, are rigidly secured to the circular asbestos plate C, said bracket arms D being connected at their lower ends to a casting E which serves as a

95 guide for the lower carbon holder F as more fully explained hereinafter.

100 One of the depending bracket arms D, is preferably flattened out or made very thin as shown in Fig. 2, in order to cast a very small or narrow shadow, and if preferred both of these brackets can be so constructed.

105 The upper carbon G, is fitted at its upper end to a sleeve G', from which extends connecting post G² to which the wire G³ is connected, said wire G³ leading from the sole-

noid H, hereinafter described in detail.

110 The upper carbon G works through a clutch I, and is lifted by this clutch. This

clutch I is pivoted at I' to the lower end of a depending rod I², which is connected at its upper end to the dash pot K, said dash pot being inverted as shown and working 5 upon piston K', supported by the rod K² secured to the upper end of the bracket K³ which is attached to a circular insulating plate C. The dash pot K is connected to the core H' of the solenoid through the medium of a coil spring H², this spring providing a yielding connection between these parts which overcomes any quick or jerking movement. It will of course be understood that when the core of the solenoid is drawn 10 up the dash pot will be carried with it which in turn raises the clutch and consequently the upper carbon.

Heretofore two solenoids have been usually employed for the purpose of carrying out the various operations of the arc lamp and one of the principal objects of my invention is to do away with one of the solenoids, and aid the single solenoid by a spring which will carry approximately one-half of the load imposed by the carbon, carbon holder, dash pot and solenoid, said spring carrying this load through the clutch to assist it in holding the carbon in operative position in either direction.

30 This coil spring L, shown most clearly in Figs. 2 and 3 is connected to the top plate or frame A by means of a screw L', and by means of which the spring as a whole can be raised or lowered to accommodate voltage changes in various sections, as it is necessary to make the lamp adjustable to the current conditions, and as one means of accomplishing this I provide for the adjustment of this spring L, which constitutes 35 one of the most important features of this lamp construction. The lower end of this spring L is connected to a Y-shaped lever M, the short leg M' of said lever being attached to the upper carbon guide by means of a rod M², while the longer and diverging legs M³ which straddle the dash pot K, are connected by rods M⁴ to the short arm of the clutch I and as such connection is on the opposite side of the fulcrum of the 40 clutch from the carbon the clutch will be shifted or turned on its pivotal point through its connection with the lever M as it is moved upwardly and downwardly by the dash pot, said movement being against 45 the tension of the spring L on downward movement of the clutch and aided by such spring on the upward movement of the dash pot. From the above description it will be understood that inasmuch as the short arm 50 of the Y-shaped lever M is fixed, it is obvious that when the dash pot carrying the clutch moves downwardly the pull exerted upon the long diverging legs of the lamp M causes a downward pull upon the spring L 55 and spring L being therefore put under ten-

sion, will materially assist in the lifting movement of the carbon, clutch, dash pot and connected parts through the medium of the lever M; and the spring L, lever M and connecting rods are of such size and so arranged with relation to each other that practically one-half of the load is carried by the spring, and consequently I am able to successfully carry out all of the functions of the arc lamp with the use of a single 70 solenoid and thereby simplify the working parts, reduce their number, and cut down the heavy starting current.

The solenoid H is held in a bracket H³ made of sheet metal and attached to the upper carbon guide B and this solenoid consists of a spool H⁴ around which the insulated wire H⁵ is wound in a peculiar manner as hereafter explained, and within the spool H⁴ is a sleeve H⁶, the ends of which are 85 turned over to connect the solenoid to the supporting bracket or carrier H³. The core is preferably of laminated construction as shown at Fig. 2, but the solid form can be employed if so desired.

90 In winding the solenoid I employ a different method from that ordinarily employed, the usual method being to employ insulating disks at the ends, in order to properly insulate the coils inasmuch as the 95 wire leading to the spool was carried entirely to the center thereof. In my construction I employ a stepped and tapered spool illustrated in Fig. 11, and around which the wire H⁵ is wound and after the 100 winding operation has been completed this stepped and tapered spool is withdrawn and the wires flattened down into the positions indicated in Fig. 4, and after being so flattened down the top of the spool is fastened 105 thereon by means of the turned over sleeve previously described. The solenoid is connected with one of the binding posts as most clearly shown, the opposite end of the solenoid being connected with the upper carbon 110 by the wire G³. The wire G⁴ leading from the other binding post is divided as shown, one portion being connected by means of binding screws to one of the globe brackets D, while the other portion is connected by 115 means of suitable binding connections to the other globe bracket D. The lower carbon G⁵ rests in the lower carbon holder F and is secured therein by means of binding screw F'. This lower holder F is formed 120 with laterally projecting guides F² which work in guide ways E² of the connecting casting E, said casting being semicircular in shape and adapted to receive the lower carbon holder and in order to hold said carbon holder in its proper position after being once adjusted I employ a spring E' which is connected at its ends to the casting E, carried rearwardly a short distance, given several coils, and then bent downwardly and 125 130

angled as shown at E³ to engage the lower portion of the casting E while the central portion of said spring is held in engagement with the lower and reduced end of the carbon holder as most clearly shown in Figs. 5, 1, 2 and 10.

The carbon holder F is formed at its upper end with a beveled shoulder F³ on which rests the flanged collar F⁴ the inner 10 edge thereof being undercut to fit the beveled shoulder F³. The globe F⁵ rests upon this flanged collar F⁴, the upper end of said globe being held against a casting F⁶, having a flange F⁷ and a depending concave 15 portion F⁸, this casting being of such shape as to fit the upper end of the globe to hold the same in place and also serve somewhat as a reflector. It will of course be understood that this casting D which in reality 20 is the upper globe holder, is attached to the under side of the circular insulating plate C. The lower carbon being held in definite position with relation to the globe brackets always maintains the lower carbon in proper 25 alinement with the upper one and is independent of any movement of the globe, and consequently the globe can be slightly tilted or shifted without disturbing the proper alinement of the carbons, which is not the 30 case with lamps in general use in which the globe holder or lower carbon holder are so connected that any movement on the part of the globe effects the position of the lower carbon. When it is desired to remove the 35 lower carbon and replace the same it is only necessary to pull back the spring E², take out the carbon holder, remove the short piece of carbon and insert a new one. The upper carbon can of course be replenished 40 easily by unscrewing the thumb nut, withdrawing the consumed piece of carbon and substituting another one.

In addition to the other special features of construction I propose to make the dash 45 pot of novel construction also. This dash pot K is inverted or arranged with its open end downward. The piston K' is a solid piece of carbon according to standard practice, in the center of which is a sleeve provided with a cross pin to which the supporting rod is attached. In the upper end of the dash pot is produced a small opening K^{2x}, this opening is surrounded upon the top of the dash pot by means of a tubular 50 extension K^{3x}, to which the lower end of the coil spring H² is connected as most clearly shown in Fig. 4^a. Within the tubular extension and covering the opening K² is a thin disk K⁴ of non-magnetic material 55 and in practice I prefer to make this disk of a diameter somewhat less than the interior diameter of the tubular extension and also provide an annular groove or recess K⁵ between said disk and tubular extension in 60 order to prevent the disk remaining open 65

during the upward stroke of the dash pot on account of the accumulation of dirt. It is necessary that the lamp should be so constructed that slight variations in current will allow the upper carbon to follow these 70 variations and therefore feed down or up as the current is reduced or increased, and in order to bring these operations about the dash pot should be subject to easy downward automatic adjustment and the construction and operation of the port and disk in connection with the yielding connection 75 with the solenoid brings about this desired operation.

Heretofore it has been usual to employ a 80 ball valve of non-magnetic material in connection with the dash pot port but the weight of this ball will cause a total weight upon the port of approximately one-half pound or in other words it would require 85 more than one-half pound difference in load to effect any change in the position of the dash pot and would therefore retard the downward action of the upper carbon due to a reduction in the current and the corresponding reduction in the pulling power of 90 the magnet with the result that the lamp would go out or at least cause it to chatter, both of which are to be avoided if possible and which will be avoided by the mechanisms herein shown and described. 95

Owing to the peculiar manner of supporting the lever M the leverage varies as the dash pot moves up and down owing to the shifting of the pivot pins of the lever and by 100 this arrangement the proper correlation or compensation between the solenoid and spring is obtained.

Having thus fully described my invention, what I claim as new and desire to secure by Letters Patent is:—

1. An arc lamp comprising a frame, an electrode, a clutch for lifting said electrode, spring means connected at one end to a stationary part of said frame and pivotally 110 connected at the other to said clutch and acting in a direction so as to tend to lift said clutch, and electromagnetic means for lifting said clutch pivotally connected to the latter between the electrode and the 115 pivotal connection of the spring means.

2. An arc lamp comprising a frame, an electrode, a clutch for lifting said electrode, spring means connected at one end to a stationary part of said frame and pivotally 120 connected at the other to said clutch and acting in a direction so as to tend to lift said clutch, and an electromagnetic means for lifting said clutch pivotally connected to the latter between the electrode and the 125 pivotal connection of the spring means and adjacent to said connection.

3. An arc lamp comprising a frame, an electrode, a clutch for lifting said electrode, spring means pivotally connected to said 130

clutch and acting in a direction so as to tend to lift said clutch, and electromagnetic means for lifting said clutch pivotally connected to the latter between the electrode 5 and the pivotal connection of the spring means, and adjacent to said point of connection.

4. An arc lamp comprising a frame, an electrode, a clutch for lifting said electrode, 10 spring means pivotally connected to said clutch and acting in a direction so as to tend to lift said clutch, electromagnetic means for lifting said clutch pivotally connected to the latter between the electrode and the 15 pivotal connection of the spring means and means connected with said spring means for varying the tension of the spring thereof.

5. In an arc lamp, the combination with a solenoid and its core, of a dash pot connected with said core, one member of said dash pot carrying a depending member, a carbon clutch pivotally connected to said depending member, a spring supported lever and a link connection between the free end 25 of said lever and the pivoted end of said clutch.

6. In an arc lamp, the combination with a carbon clutch, of a solenoid, a spring supported lever fixed at one end and connected 30 at its opposite end with the end of said clutch, connecting means between the solenoid and clutch, said connecting means being connected to the clutch between the electrode and the pivotal connection with the 35 spring supported lever.

7. In an arc lamp, the combination with a solenoid and its core, of a dash pot connected with said core and having a depending portion, a carbon clutch, a lever fixed at 40 one end, a spring support for said lever, a link connecting the free end of said lever with the end of carbon clutch, the depending portion of said dash pot being pivotally connected to the carbon clutch between the 45 electrode carrying end and the link connection.

8. In an arc lamp, the combination with a solenoid and its core, of a dash pot con-

nected with said core, a fixed piston upon which said dash pot works, a carbon clutch, 50 a spring supported lever having pivotal connection with the end of the clutch, said dash pot having a depending portion pivotally connected to the clutch between the ends of clutch and adjacent to the pivotal connection with the lever.

9. In an arc lamp, the combination with a solenoid, of a dash pot connected with the core thereof and operated thereby upon a fixed piston, a carbon clutch, a spring, a 60 lever pivoted at one end and bifurcated to straddle the dash pot, the bifurcated end being pivotally connected with the end of said clutch, said dash pot having a portion pivotally connected to the clutch between its 65 pivoted end and its electrode carrying end.

10. In an arc lamp, the combination with a carbon guide, of a solenoid carried thereby, a dash pot connected with the core of said solenoid and movable thereby upon a 70 fixed piston, a carbon clutch, a spring support, a lever connected thereto, one end of said lever being pivotally connected to the carbon guide and the opposite end of said lever being pivotally connected to the carbon clutch and means connecting the dash pot with the carbon clutch between its 75 pivotal end and its carbon carrying end.

11. In an arc lamp, the combination with a carbon guide, of a solenoid carried thereby, a dash pot yieldingly connected with said solenoid and movable thereby upon a fixed piston, a carbon clutch, an adjustable spring support, a lever connected thereto, one end of said lever being pivotally connected to the carbon guide, the opposite end of said lever being pivotally connected to the carbon clutch, and a depending member carried by the dash pot and pivotally connected to the carbon clutch between its 80 90 pivoted end and its carbon carrying end.

JAMES H. WAGENHORST.
